Victor Tanier

By *June Daniels, Esq.*
Attorney

UNITED STATES PATENT OFFICE.

VICTOR TANIER, OF SCLAIQUEAUX, BELGIUM.

FURNACE.

Application filed February 5, 1923. Serial No. 617,068.

To all whom it may concern:

Be it known that I, VICTOR TANIER, engineer, a subject of the King of Belgium, residing at Sclaigneaux, in the Kingdom of Belgium, have invented certain new and useful Improvements in Furnaces, of which the following is a specification.

This invention has for its object to provide an improved furnace wherein the heating chamber is composed of two halves separated by a longitudinal partition, and it relates more especially to regenerator furnaces designed for heating crucibles for effecting the reduction of ores.

15 Furnaces of this type are known, particularly those wherein the crucibles are arranged in a certain number of horizontal rows situated above one another, having a combustion chamber beneath the bottom row. 20 In that known construction, the products of combustion ascend from one row to another up to the highest row through half of the heating chamber on one side of the furnace, and then descend through the other 25 half of the heating chamber.

In other known types of furnaces, the path of the products of combustion is the reverse, namely down on one side of the furnace and then up on the other side of the 30 furnace.

35 In a third known type of furnace, the combustion chamber is arranged between the two halves of the heating chamber. The burnt gases fill the heating chamber, descend to some extent, and pass off to the regenerators.

40 That type of furnace has the great drawback that there is not a regular and uniform heating throughout the heating chamber which is an essential quality of a furnace giving a really economical output.

The reduction is not effected simultaneously. The crucibles in the bottom row (or top row) are subjected to a more intense 45 heat than the other rows, thus entailing a rapid deterioration.

With the object of obviating all those drawbacks and obtaining a temperature as constant as possible throughout the entire 50 length of the heating chamber, the present invention comprises the following features:—

1. Complete separation between the two halves of the heating chamber by means of 55 a longitudinal partition which extends up

to the roof of the furnace and renders the two halves of the heating chamber quite independent of each other, thus allowing of heating each half independently. The ducts for supplying and discharging the gases are 60 formed in the aforesaid longitudinal partition. The flow of the gases in the furnace takes place in a longitudinal direction. By blocking the orifices of the gas ducts supplying one of the halves of the heating 65 chamber, the said half is placed completely out of action, so that it can be repaired or altered while the other half of the heating chamber is kept working;

2. Regulation of the supply of air and gas 70 by subdividing the regenerators into independent sections. By this means it is possible to regulate the supply of air and gas in every part of the heating chamber.

By increasing the supply to the parts that 75 are insufficiently heated, and reducing the supply to the parts that are overheated, the heating can be so regulated as to obtain an almost uniform temperature throughout the length of the heating chamber.

In the case of a certain number of rows 80 the air and gas supply apertures may be so arranged as to allow gas only, or air only, or both gas and air together to enter the heating chamber at the level of each row of 85 crucibles.

In that instance, the present invention provides also another means for enabling the temperature to be regulated under each row, for which purpose a cross partition is 90 arranged in the middle of the heating chamber. This cross partition is provided with apertures situated at different levels. By blocking these apertures more or less, the gases are compelled to follow any desired 95 path. By this means therefore the flow of the gases can be increased underneath some of the rows, and diminished underneath other rows.

The accompanying drawings illustrate by 100 way of example a constructional form of the improved regenerator furnace designed for heating crucibles in a plurality of horizontal rows arranged above one another.

In these drawings:—

Figure 1 is a vertical section of one half 105 of the furnace taken along the lines *a*—*b* of Figure 2 and *g*—*g'* of Figure 4 on double the scale of other figures.

Figure 2 is a horizontal section of the 110

furnace taken along the lines *c-d* of Figure 1 and *e-f* of Figure 3.

Figure 3 is a vertical section of the other half of the furnace taken along the lines *h-h'* of Figure 2 and *i-j* of Figure 5.

Figure 4 is a horizontal section of the furnace taken along the line *k-l-l'-m-m'-n* of Figure 5.

Figure 5 is a transverse section of the furnace taken along the line *o-o'-p-p'* of Figures 2 and 4.

As shown, the improved furnace comprises a heating chamber divided by a longitudinal partition 1 into two entirely independent halves 2 and 3 (Figure 5).

The ducts 4 and 5 for supplying the air and gas are formed vertically in the longitudinal partition 1 throughout the length of the heating chamber in such a manner that an air duct is situated by the side of a gas duct. These ducts communicate through flues 6 and 6' with the four regenerators 7, 8, and 7', 8' situated at the two longitudinal sides of the furnace. Also, two or more air ducts may be provided for one gas duct.

The air and gas, coming from the gas main 13 or air main 14, pass into the regenerators, for instance 7 and 8, that are then working, wherein they become heated and pass along the flues 6 and 6' into the vertical ducts 4 and 5 formed in the wall 1.

In the construction illustrated in Figure 5, where the crucibles are arranged in four horizontal rows one above another, the ducts 4 and 5 are provided with apertures 15 and 16 on a level with each row of crucibles. Horizontal ducts 17 and 18 supply air and gas in the proximity of each row where combustion takes place. The products of combustion pass along the heating chamber until they meet a cross partition 21 in the middle of the heating chamber. The burnt gases then pass through the apertures 22 formed in the cross partition 21 at the levels of the various rows, and they arrive at the other end of the heating chamber at the horizontal ducts 17' and 18' at the apertures 15' and 16' and at the vertical ducts 4' and 5' on their way to the regenerators 7' and 8' which are thereby heated up.

After the reversal the gases travel in the reverse direction.

For the purpose of enabling the heating to be regulated as desired, the air and gas regenerators are subdivided according to this invention into independent compartments 11 for the air and 12 for the gas. The air and gas enter by way of the air mains 13 and gas mains 14 into the said compartments through apertures 19 provided in each compartment. Each of these apertures 19 is adapted to be closed by a damper for the purpose of regulating the quantity of air or gas passing through. In the illustrated example the several apertures 19

may be closed to a greater or less extent by means of a brick 19'. Apertures 20 closed by plugs 20' (capable of being withdrawn for obtaining access to the bricks 19') are provided opposite the apertures 19 in the air and gas mains.

What I claim is:

1. A regenerator furnace having a heating chamber divided into two halves by a longitudinal partition, said partition extending up to the roof of the furnace so as to completely separate said halves of the heating chamber, regenerators situated at both ends of the heating chamber, said regenerators being in communication with said halves of the furnace, and means for dividing the air and gas coming from the regenerators arranged at one end of the heating chamber into two streams directed each into one of the halves of the heating chamber. 75

2. A regenerator furnace having a heating chamber divided into two halves by a longitudinal partition, said partition extending up to the roof of the furnace so as to completely separate said halves of the heating chamber, regenerators situated at both ends of the heating chamber, said regenerators being in communication with said halves of the furnace, means for dividing the air and gas coming from the regenerators arranged at one end of the heating chamber, and means for collecting at the other end of the heating chamber the burnt gases escaping from the heating chamber so as to direct said burnt gases into the regenerators situated at the other end of the heating chamber. 90

3. A regenerator furnace having a heating chamber divided into two halves by a longitudinal partition, said partition extending up to the roof of the furnace so as to completely separate said halves of the heating chamber, regenerators situated at both ends of the heating chamber, said regenerators being in communication with said halves of the furnace, and a plurality of vertical ducts provided side by side in said longitudinal partition, each one of any two adjacent ducts communicating with a different one of the two regenerators situated at 110 the same end of the heating chamber, said ducts being provided with apertures connecting them with the two halves of the furnace. 115

4. A regenerator furnace having a heating chamber divided into two halves by a longitudinal partition, said partition extending up to the roof of the furnace so as to completely separate said halves of the heating chamber, crucibles arranged in a plurality of horizontal rows, said rows being arranged above one another, a plurality of vertical ducts provided side by side in said longitudinal partition, each one of any two adjacent ducts communicating with a dif- 120

125 130

ferent one of the two regenerators situated at the same end of the heating chamber, said ducts being provided with apertures connecting them with the two halves of the furnace, said apertures being disposed at different levels so as to supply air and gas in the proximity of each row of crucibles.

5. A regenerator furnace having a heating chamber divided into two halves by a longitudinal partition, said partition extending up to the roof of the furnace so as to completely separate said halves of the heating chamber, crucibles arranged in a plurality of horizontal rows, said rows being arranged above one another, a plurality of vertical ducts provided side by side in said longitudinal partition, each one of any two adjacent ducts communicating with a different one of the two regenerators situated at the same end of the heating chamber, said ducts being provided with apertures connecting them with the two halves of the furnace, said apertures being disposed at different levels so as to supply air and gas in the proximity of each row of crucibles, and means for compelling the gases to follow any desired path during their passage through the heating chamber.

6. A regenerator furnace having a heating chamber divided into two halves by a longitudinal partition, said partition extending up to the roof of the furnace so as to completely separate said halves of the heating chamber, crucibles arranged in a plurality of horizontal rows, said rows being arranged above one another, a plurality of vertical ducts provided side by side in said longitudinal partition, each one of any two

adjacent ducts communicating with a different one of the two regenerators situated at the same end of the heating chamber, said ducts being provided with apertures connecting them with the two halves of the furnace, said apertures being disposed at different levels so as to supply air and gas in the proximity of each row of crucibles, and a cross partition furnished with apertures provided in each half of the heating chamber.

7. A regenerator furnace having a heating chamber divided into two halves by a longitudinal partition, said partition extending up to the roof of the furnace so as to completely separate said halves of the heating chamber, crucibles arranged in a plurality of horizontal rows, said rows being arranged above one another, a plurality of vertical ducts provided side by side in said longitudinal partition, each one of any two adjacent ducts communicating with a different one of the two regenerators situated at the same end of the heating chamber, said ducts being provided with apertures connecting them with the two halves of the furnace, said apertures being disposed at different levels so as to supply air and gas in the proximity of each row of crucibles, said regenerators being divided into a number of separate and independent compartments, each of said compartments being connected with one of said vertical ducts.

In testimony whereof I affix my signature.

VICTOR TANIER.
